UNITED STATES PATENT OFFICE.

ARTHUR W. SMITH, OF NEW YORK, N. Y., ASSIGNOR TO REMINGTON TYPEWRITER COMPANY, OF LION, NEW YORK, A CORPORATION.

TYPE-WRITING MACHINE.

1,192,577.

Specification of Letters Patent. Patented July 25, 1916.

Application filed April 27, 1916. Serial No. 93,862.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

- 10 My present invention relates particularly to paper controlling, guiding and feeding mechanism for typewriting machines and its general object is to provide improved mechanism of the character specified.
- 15 More specifically stated, one object of the invention is to provide an improved end gage and another object is to provide an improved pressure device or paper finger contrivance.
- 20 Another object is to improve certain features in the construction disclosed in the patent to Phelps No. 1,100,442, granted June 16, 1914.

To the above and other ends my invention consists in the features of construction, combinations of devices and arrangements of parts to be hereinafter described and particularly pointed out in the claims.

In the accompanying drawings, Figure 1 is a fragmentary end view, partly in section, of the upper portion of a No. 11 front-strike Remington typewriting machine embodying my invention. Fig. 2 is a fragmentary perspective view of one of the end stops or gages and associate parts. Figs. 3 and 4 are end views, partly in section, showing the end stop and associate parts in different positions. Fig. 5 is an end view, partly in section, showing the relationship of the parts when certain of the feed roll devices are released. Fig. 6 is a fragmentary front elevation, partly in section, showing the platen carriage with my improvements applied thereto. Fig. 7 is a fragmentary perspective view of my improved pressure device or paper finger contrivance. Figs. 8 and 9 are detail views of certain of the feed roll devices.

Referring first to Figs. 1 and 6, the main frame of the machine is shown as comprising

ing a top plate 1, having a trough or depression 2. Above the top plate are stationary grooved guide rails 3 and 4 with which coöperate through rollers 5 with the grooved front and rear bars numbered respectively 6 and 7 of a rectangular carriage truck which further comprises end bars 8. A platen frame or carrier comprising end bars or plates 9 and a connecting cross bar or bridge piece 10, is in the present instance, 60 rigidly mounted on the carriage truck as in the Phelps patent aforesaid. The carriage comprising said truck and said platen frame provides a support for a rotary platen 11 which is arranged above the cross bar 10. 65 The cross bar 10 is provided at its rear side with upstanding lugs 12 which are arranged at intervals lengthwise of the bar and provide a bearing for a hollow rod or rock shaft 13. Extending through the hollow shaft 70 13 is a release rod or rock shaft 14 which bears at its ends in the end bars 9. At its left-hand outer end the rock shaft 14 is provided with a crank arm 15 which is pivotally connected with the lower end of an eccentric strap 16, the upper end of said strap coöperating with an eccentric 17 provided with a finger piece or key 18 and pivoted at 19 to the end bar 9. Bearing on the hollow shaft 13 are pairs of hanger arms 20, 80 each pair carrying a shaft 21 on which are mounted the sections 22 of feed rollers. Springs 23 connected to the hanger arms 20 and anchored to the cross bar 10 tend to keep the feed rollers 22 in operative relationship with the underside of the platen 11. The feed rollers 22 may be thrown off automatically during endwise movements of the carriage by devices comprising a releasing member 24 fixed to the rock shaft 13 and 90 extending downward therefrom in position to coöperate with a device or wheel 25 mounted in the bottom of the trough 2 to effect a rocking of the shaft 13. This rocking or turning movement of the shaft is independent of the shaft 14 and is transmitted to the hanger arms 20 by fingers 26 fixed to the rock shaft and provided with lateral pins 27 which overlie said hanger arms. The relationship of the parts 25 and 100

24 when the feed rollers 22 are operative is shown in Fig. 1. By moving the carriage leftward far enough the lower end of the device 24 engages with and is operated by 5 the wheel 25, rocking the shaft 13 and throwing off the feed rollers 22 as will be understood from Fig. 5. The point in the carriage travel at which the feed rollers 22 are automatically thrown off as described 10 depends upon the location of the roller 25 which may be varied. It will be understood that this automatic throw-off of the feed rollers occurs during movement of the carriage in either direction whenever the part 15 24 operatively engages with the roller 25, and that as soon as the part 24 passes out of engagement with the roller 25 the feed rollers will be restored to operative position by the springs 23. The feed rollers 22 are between or intermediate terminal or marginal 20 feed rollers 28 which are controlled by the release shaft 14 which in turn is controlled by the key 18.

The construction of the rollers 28 and their 25 mountings will best be understood from Fig. 2. Each terminal roller 28 comprises a sheath 29 of rubber or the like and a core 30, the core projecting outward beyond the sheath and having reduced end portions 31 which 30 bear in parallel arms 32 of a U-shaped support or hanger 33 that further comprises a connecting cross piece 34 joining the arms 32. The arms 32 have perforated bearing portions and the outer arm of each terminal 35 hanger 33 bears on the rock shaft 14 while the inner arm bears on the shaft 13 as will be understood from Figs. 6 and 8, the latter being an enlarged sectional view of the left-hand hanger 33 and associate parts 40 taken through and lengthwise of the rock shaft 13. Draw springs 35 connect the hangers 33 with the cross bar 10 and tend to keep the feed rollers 28 in co-operative engagement with the platen. The terminal 45 feed rollers 28 are in line with the intermediate feed rollers 22, both sets being housed by the bar 10, but the rollers 28 are not controlled by the automatic devices 24 and 25. Said rollers 28 are releasable by 50 fingers 36 fixed to the rock shaft 14 and provided with lateral pins 37 which overlie the outer hanger arms 32, the construction being such that when the key 18 is pushed rearward from the Fig. 3 to the Fig. 4 position 55 55 the pins 37 will operate on the hangers 33 to release the terminal feed rollers. Collars 38 fixed to the rock shaft 14 prevent inward displacement of the hangers 33 lengthwise of said shaft. Means are also provided 60 for releasing the intermediate feed rollers 22 when the feed rollers 28 are released by the key 18, said means comprising two collars 39 (Figs. 6, 8 and 9), which collars are fixed to the rock shaft 14 just beyond the 65 ends of the hollow shaft 13. Each collar 39

is undercut to provide shoulders 40 and the end portions of the shaft 15 are correspondingly cut to provide underlying shoulders 41. The normal relationship of these shoulders is best understood from Fig. 9 which is an enlarged sectional view taken transversely through the shaft in Fig. 8 and looking inward toward the middle of the machine. When the key 18 is swung rearward from the Fig. 3 to the Fig. 4 position the 70 forward shoulders 40 on the collars 39 engage with the underlying shoulders 41 on the shaft 13 and turn said shaft to effect a releasing movement of the feed rollers 22 concurrently with the release of the feed 75 rollers 28. When the key 18 is swung back to the Fig. 3 position the feed rollers are restored by their springs. As shown in Fig. 9 the shoulders 41 and 40 at the rear side of the shaft 14 are normally separated to provide lost motion, thus affording a turning movement of the shaft 13 under an actuation of the automatic devices 24 and 25 without affecting the collars 39 and the 80 shaft 14. A paper table 42 is supported on the platen frame above and to the rear of the platen and below the paper table is a paper apron or deflector 43 which curves downward behind and under the platen terminating below the printing line at the forward side thereof. The apron 43 is secured to blocks 44 which are rotatable on the shaft 13. The feed rollers co-operate with the platen through openings 45 in the paper apron, the outer or end openings accommodating not only the terminal feed rollers 28 but also the novel end stop devices next to be described.

The end stop devices or gages 46 are preferably formed of sheet metal and are of a shape best shown in Fig. 2. Each sheet metal plate 46 is provided with an upturned forward end 47 forming the end stop proper. At its sides the plate 46 has rearwardly extending fingers 48 which are curled loosely around the extended portions of the core or axis piece 30 and thus provide a loose pivotal connection between the end stop and the feed roller and its hanger or support 33. At all times the end 105 stops rest forward of their pivots against the upstanding pointed end 10^a of the cross bar 10 which provides a fixed abutment that is in the nature of a fulcrum for the end stop devices. The normal or inoperative position of these end stop devices is shown in Figs. 1 and 3. When the release key 18 is swung backward to the Fig. 4 position to release all the feed rollers the rear or pivotally connected end portions of the 110 end stop devices 46 are swung downward and backward, causing said devices to slide over the abutments 10^a and elevating the forward portions or stops proper 47 until said stops 115 are brought into operative relationship with 120 the feed rollers 22. The end stop devices 46 are 125 pivoted to the rock shaft 14 just beyond the 130 ends of the hollow shaft 13.

the platen as shown in Fig. 4. With the parts in this relationship a wide sheet may be inserted into the machine and accurately positioned lengthwise by the aid of the stops 47, after which the release key is returned, causing the restoration of the rollers to working position and withdrawing the stops 47 which slide forward over the abutment 10^a and also fulcrum on the same. The stop 10 devices, it will be noted, may be regarded as levers of the first order. It will be understood that during endwise movements of the carriage that may cause automatic releasing of the intermediate feed rollers 22 15 the end stops 47 will not be affected, the construction being especially designed for use with sheets of different widths, *i. e.*, wide sheets and sheets somewhat narrower than the wide sheets, the latter being controlled 20 primarily by the terminal feed rollers and the end stops. My improved end stops are simple in design and positive in operation, dispensing with the use of springs and complicated parts which are liable to get out of 25 order.

Other novel paper controlling devices are provided, said devices comprising paper fingers which are preferably in skeleton form and coöperate with the front face of the 30 platen, said paper fingers being mounted on arms which are adjustable on and extend rearward from a spring-pressed rod which may be rocked to throw the paper fingers simultaneously upward and forward away 35 from the printing face of the platen. Referring particularly to Figs. 1, 6 and 7, 49 is a rod or rock shaft that extends lengthwise of the platen and is arranged some distance in front of its printing face, said rod 40 bearing at its ends in brackets 50 rigid with the front bar 6. The upper face of the rod is flattened as indicated at 51. Collars or hubs 52 are arranged on the rod, two collars being shown in the present instance, 45 each collar being provided with a thumb screw 53 which coöperates with the flat face 51 to hold the hub in adjusted position lengthwise of the rod. Rigid with the hub 52 and projecting therefrom is an arm 54 50 which is provided at its rear end with an angular extension or inwardly projecting stub rod or shaft 55, the stub shafts extending parallel with the platen axis and carrying each a paper finger 56. Said paper finger is in the present instance made of wire bent to the shape of a Y, the upper ends or branches being secured in the end portions of the associate stub shaft. The paper finger extends downward across the printing line on the front face of the platen and its lower contracted end projects below the upper edge of the paper apron 43. Arranged on each stub shaft and confined between the arm 56 and one of the branches 60 65 of the paper finger is a pressure device or

roller 57. The pressure devices or paper finger contrivances, comprising the paper fingers 56 and the pressure rollers 57 confined within them, may be adjusted lengthwise of the platen toward and away from each other by loosening the thumb screws 53 and pushing the arms 54 inward or outward. Said contrivances are normally maintained spring pressed in coöoperative engagement with the platen by draw springs 75 58 which are anchored to the brackets 50 and are also connected to arms 59 rigid with the rock shaft 49. By pulling upward on either of the arms 54 the paper fingers may be simultaneously released, being swung upward and forward away from the platen as shown by dotted lines in Fig. 1. When they are down in engagement with the platen it will be observed that the entire front and upper face of the platen between 80 85 the paper fingers and the upper edge of the paper apron 43 is left entirely free and unobstructed.

Various changes may be made without departing from my invention.

What I claim as new and desire to secure by Letters Patent, is:—

1. In a typewriting machine, the combination of a platen carrier, a platen thereon, an end stop, a support on which said end stop is loosely mounted, an abutment against which said end stop rests, and means for moving said support and thereby causing movement of said end stop to operative relationship with said platen, said end stop remaining throughout such movement in contact with said abutment.

2. In a typewriting machine, the combination of a platen carrier, a platen thereon, a support movable by a hand operation, an end stop device pivoted to said support, and an abutment against which said stop device rests, said stop device sliding over said abutment to the operative relationship with the platen when said hand controlled support is moved.

3. In a typewriting machine, the combination of a platen carrier, a platen thereon, a movable support controlled by hand, an end stop device pivoted at one of its ends to said support and provided at its opposite end portion with an end stop proper, and an abutment intermediate the ends of said device and against which said device rests, said device sliding over said abutment to operative relationship with the platen when said support is moved.

4. In a typewriting machine, the combination of a platen carrier, a platen thereon, a hand controlled pivoted end stop device, and an abutment against which said end stop loosely rests and over which it slides to operative position.

5. In a typewriting machine, the combination of a platen frame, a platen thereon, a

- feed roller, a feed roller carrier, an end stop loosely supported on said carrier, and an abutment over which said end stop slides to operative position when said feed roller is released. 5
6. In a typewriting machine, the combination of a platen frame, a platen thereon, a feed roller carrier therefor, a key or finger piece, connections between said key and said feed roller carrier, an end stop loosely mounted on said carrier, and an abutment by which said end stop is supported and over which it slides into and out of operative position when said key is actuated. 10
15. 7. In a typewriting machine, the combination of a platen frame, a platen, a rod or bar on said platen frame, a feed roller, a carrier therefor pivoted on said rod or bar, key connections operative on said carrier to release said roller, an end stop device loosely connected to said roller, and an abutment rigid with said frame on which said stop device constantly rests. 20
8. In a typewriting machine, the combination of a platen frame, a platen, a rod or bar on said platen frame, a feed roller, a carrier therefor pivoted on said rod or bar, hand controlled means operative on said carrier to release said roller, an end stop device pivotally supported from said carrier, and an abutment on which said end stop device rests and over which it is adapted to slide into and out of operative position when said hand controlled means is actuated. 30
35. 9. In a typewriting machine, the combination of a platen, a platen frame on which said platen is mounted, said platen frame comprising a cross bar underlying said platen, a key controlled rod extending lengthwise of the platen, feed roller carriers mounted on said rod, feed rollers pivoted on said carriers, springs operative on said carriers and to press said feed rollers into operative engagement with the platen, and end stop devices pivoted co-axially with said feed rollers and resting loosely on said cross bar, said end stop devices sliding over said cross bar to operative position when said key controlled rod is actuated. 40
50. 10. In a typewriting machine, the combination of a platen, a platen frame on which said platen is mounted, said platen frame comprising a cross bar underlying said platen, feed roller carriers pivotally mounted in rear of said platen, feed rollers pivoted on said carriers and spring pressed toward the platen, and end stop devices supported by said carriers, said end stop devices being pivoted co-axially with said feed rollers and resting loosely against said cross bar, said end stop devices sliding into operative relationship with the platen when said carriers are released and said feed rollers withdrawn from co-operation with said platen. 55
11. In a typewriting machine, the combination of a platen, a platen frame comprising a cross bar underlying said platen, a key controlled rod extending lengthwise of the platen in rear thereof, spring pressed feed 70 roller carriers mounted on said rod, feed rollers pivoted on said carriers, a paper apron pivoted co-axially with said rod and provided with openings through which said feed rollers may co-operate with the platen, 75 and end stop devices pivoted co-axially with said feed rollers and resting loosely on said cross bar, said end stop devices sliding over said cross bar to operative position through said openings when said key controlled rod 80 is actuated. 85
12. In a typewriting machine, the combination of a platen, a platen frame, a U-shaped carrier having parallel arms, a feed roller pivoted on said carrier and arranged between said arms, and an end stop device having extensions which pivotally engage with the axis of said feed roller between said parallel arms. 90
13. In a typewriting machine, the combination of a platen, a platen frame, a U-shaped carrier having parallel arms, a feed roller pivoted on said carrier and arranged between said arms, an end stop device having extensions which pivotally engage with 95 the axis of said feed roller between said parallel arms, spring means operative on said carrier to press said feed roller constantly toward said platen, and an abutment rigid with said frame and on which 100 said end stop device loosely rests. 105
14. In a typewriting machine, the combination of a platen, marginal pressure roll devices, intermediate pressure roll devices, means for automatically releasing said intermediate pressure roll devices, separate hand controlled means for releasing said marginal pressure roll devices, and marginal stop devices that are brought to operative position when said marginal pressure 110 roll devices are released. 115
15. In a typewriting machine, the combination of a platen carrier comprising a cross bar, a platen mounted on said carrier and arranged above said cross bar, marginal pressure roll devices, intermediate pressure roll devices, means for automatically releasing said intermediate pressure roll devices, separate hand controlled means for releasing said marginal pressure roll devices and marginal stop devices that are brought to operative position when said marginal pressure roll devices are released, the cross bar providing a housing for said pressure rolls and the end stops sliding over said cross bar 120 which constantly supports them. 125
16. In a typewriting machine, the combination of a platen, a fixed abutment or fulcrum, a lever device resting on said fulcrum and provided at one end or arm with an end 130

stop proper, and key connections to the other arm of said lever device.

17. In a typewriting machine, the combination of a platen, a feed roller, a feed roller carrier, a lever device pivotally connected to said carrier at one arm, an end stop connected to the other arm of said device, and an abutment or fulcrum with which said device coöperates.

Signed at the borough of Manhattan, city 10 of New York, in the county of New York, and State of New York, this 26th day of April, A. D. 1916.

ARTHUR W. SMITH.
